Application June 1, 1933, Serial No. 673,838

11 Claims. (Cl. 200—87)

This invention relates to electrical switching devices and more particularly to such devices in which the contacts are operated in an evacuated chamber.

5 One object of this invention is to prevent arcing between the contacts in electrical switching devices which are adapted for use in high voltage circuits.

Another object of the invention is to provide 10 a switching device which will be effective in reduced atmosphere such as at high altitudes.

In one embodiment of this invention, a switching device comprises a pair of normally open contacts supported in operative relation in a vessel, 15 which may be highly evacuated. One of the contacts is movable and is actuatable by an electromagnet supported externally of the vessel.

A feature of this invention relates to a substantially non-frictional guiding support for the 20 movable contact assembly.

Other features of this invention relate to a shock-absorbing mounting for a contact point in the body of the movable contact assembly to eliminate sparking upon the closure of the contacts and to a movable contact assembly of large 25 mass which serves as a gravity-actuated member to break the engagement between the contacts quickly upon deenergizing of the electromagnet.

A further feature of this invention relates to a 30 novel support for the electromagnet exteriorly of the vessel, comprising a collar having a plurality of fingers to engage a tubular core carrying the electromagnet winding.

Further features of this invention relate to a 35 retractile spring for restoring the movable contact to its normal or open position and to the provision of a non-inductive current carrying flexible link member of negligible tension connected to the movable contact, whereby the use 40 of the retractile spring as a current conductor is obviated and deterioration of the spring is prevented.

The invention and the various features thereof 45 will be understood more clearly and fully from the following detailed description with reference to the accompanying drawing in which:

Fig. 1 is a perspective view of an electrical 50 switching device illustrative of this invention, with the electromagnet in cross-section, with means for securing the electromagnet and device together. Portions of the enclosing vessel are broken away to show the contact assemblies more clearly;

55 Fig. 2 is an enlarged view in cross-section of

portions of the contact assemblies of the device shown in Fig. 1; and

Fig. 3 is an enlarged perspective view of the 5 movable contact showing in detail the shape of the groove in the contact and the relationship of the dislocated contact to the guide supports.

Referring now to the drawing, the switching device of this invention includes a vitreous enclosing vessel having a bulbous portion 10 and an elongated tubular portion 11, the vessel preferably being highly evacuated. A metallic cap or terminal 12 is mounted on an insulating disc 13 and is secured to the bulbous portion 10, and a similar metallic cap or terminal 14 is secured to the tubular portion 11. The tubular portion 11 is provided with a reentrant stem 15 in which there is embedded a metallic rod 16 which is electrically connected to the cap or terminal 14 and has secured to one end thereof a contact 17, of tungsten or the like. A metallic member 18, which 20 may be of a magnetic material such as iron, and may be chromium plated to prevent corrosion thereof, has an integral annular shoulder 19 of slightly greater height than the contact 17, is mounted upon the rod 16 and is provided at one 25 end with a recess in which the contact 17 is seated. The member 18 is preferably of appreciable mass and prevents excessive jarring of the contact 17 during the operation of the switching device.

The bulbous portion 10 is provided with a re- 30 entrant stem 19 terminating in a press 20 in which a pair of rigid parallel guides or rods 21 are embedded. The rods 21 extend within the tubular portion 11 and are spaced and interconnected by a bent strap or stop 22. A movable contact assembly is disposed between the rods 21 and includes a cylindrical mass or body member 23 of a magnetic material, such as iron, having a pair of diametrically disposed V-shaped 35 guide grooves 24 in its outer longitudinal surface 40 for accommodating the rods 21. Because of the shape of the grooves a relatively small contact surface exists between the rods 21 and the body 23 so that a very small frictional force is present 45 when the body moves along the rods. The rods 21 and grooves 24 are so disposed that the body 23 is in axial alignment with the mass member 18. The body 23 may be chromium plated to prevent corrosion thereof and to provide a bearing 50 surface in the grooves of very low friction, and is provided with an axial bore through which a rod 25 extends. A contact 26, which may be of tungsten, is mounted upon one end of the rod 25, and a collar or button 27 is secured to the rod adjacent the other end thereof and abuts 55

against one end of the body 23 as shown in Fig. 2. A helical spring 28 is disposed within the bore in the body 23 and abuts at one end against the contact 26 and at the other end against a shoulder 5 or seat 29 within the body 23.

The rod 25 is connected at the end toward stem 10 to a retractile spring 30 secured to a bent wire 31 embedded in the press 20. A non-inductive conductor such as a folded flexible ribbon 10 or spring 32 is connected at one end of the rod 25 and at the other end to a stub or short wire 50 embedded in the press 20 and electrically connected to the terminal 12 by a conductor 33. The folded flexible member or spring 32 obviates 15 the use of the retractile spring 30 as a current carrying member so that deterioration of the spring 30, which might result from a current flow therethrough, is prevented.

A collar or support is secured about the bulbous portion 10 and comprises two similar semi-cylindrical portions 34, each having a plurality of fingers 35 extending parallel with and toward the tubular portion 11 of the vessel from one end of the collar. The collar is also provided 25 with juxtaposed flanges 36 through which bolts 37 extend. An electromagnet is coupled to the collar, and comprises an annular coil 38 which encircles a tube or core 39 of non-magnetic material, for example, brass, adapted to encircle the tubular portion 11 of the enclosing vessel. The ends of the tube or core 39 are spun over 30 annular plates 40 of magnetic material, for example, iron, disposed adjacent the bases of the coil 38 and spaced therefrom by insulators 41. A flanged tubular member 42 of non-magnetic material is secured in any convenient manner, for example, by rivets 43, to one of the plates 40 and is adapted to fit within the fingers 35 and may be clamped in position by a band or collar 44 which encircles the fingers 35. An insulating block 46, on which terminals 48 for the coil 38 are mounted, is secured to the end plates 40 by eyelets 47. The plates 40 are provided with extensions or lugs 49 through which the switching device may be secured to a suitable support. 45

The operation of the switching device in an electrical circuit is as follows: Normally, the contacts 17 and 26 of the switching device are spaced apart as indicated in Fig. 2, and the movable mass or body 23 rests upon or abuts against the strap or stop 22. When it is desired to close a circuit, the coil 38 is energized from a suitable source and the magnetic field produced acts upon the body 23 and causes it to move toward the stationary member 18 against the tension of the retractile spring 30. Inasmuch as the member 18 is of appreciable mass an efficient magnetic circuit is provided. The movement of the body 23 brings the contact 26 into engagement with the contact 17, the spring 28 acting as a buffer or cushion to prevent jarring of the contacts 17 and 26 and also to maintain a good engagement between the contacts so that arcing is prevented. The shoulder 5 prevents excessive depression of the contact 26 relative to the body member 23. When the coil 38 is deenergized, the member 23 moves away from the stationary member 18 through the action of the spring 30 and the engagement between the contacts 17 and 26 is broken. Inasmuch as the body 23 is of appreciable mass, if the switching device is supported vertically in the position shown in Fig. 1, the gravitational force is relatively great and a quick break between the contacts 17 and 26 75 is obtained so that arcing between the contacts

is prevented. The movement of the body 23 away from the stationary contact assembly is limited by the strap or stop 22.

Since the contacts operate in a high vacuum, 5 arcing or flashover is prevented. Furthermore, the operating characteristics of the switching device are independent of external conditions so that the device is particularly suitable for use in apparatus, for example, radio apparatus or aircraft, which may be operated in rarefied atmospheres at high altitudes as well as in approximately normal atmospheres. 10

It will be understood, of course, that many modifications may be made in the embodiment 15 of the invention shown and described without departing from the scope and spirit of this invention as defined in the appended claims.

What is claimed is:

1. An electrical switching device comprising an enclosing vessel, a plurality of assemblies having 20 contacts thereon mounted in cooperative relation within said vessel, one of said assemblies being movable, means for actuating said movable contact, and a plurality of guide members engaging spaced portions only of said movable assembly 25 for aligning the contact thereon with respect to another of said contacts, said movable assembly including means cooperating with said guide members to prevent rotation of said movable assembly. 30

2. An electrical switching device comprising an enclosing vessel, a stationary contact within said vessel, a movable contact assembly within said vessel including a body member and a contact on said body member, means for actuating said movable assembly, and a plurality of guide members engaging only spaced limited portions of the outer surface of said body member and aligning the movable contact with respect to said stationary contact. 35

3. An electrical switching device comprising an enclosing vessel having a stem, a stationary contact within said vessel, a movable contact assembly in alignment with said stationary contact including a body member having a plurality of longitudinal grooves in its outer surface, means for actuating said contact assembly, and a plurality of guide members extending from said stem and in contact with walls of said grooves. 45

4. An electrical switching device comprising an 50 enclosing vessel, a stationary contact within said vessel, a movable contact adjacent said stationary contact, and means exterior to said vessel for actuating said movable contact including a tubular member encircling said vessel, a magnetic 55 coil surrounding said tubular member, a collar about said vessel having projections engaging said tubular member, and means clamping said projections against said tubular member.

5. An electrical switching device comprising 60 an enclosing vessel of insulating material, a plurality of contacts within said vessel, one of said contacts being movable, a terminal on said vessel, a retractile spring fixed at one end to said vessel and connected at the other end to said movable 65 contact, and means insulated from said spring at one end by said vessel and electrically connecting said movable contact to said terminal.

6. An electrical switching device comprising an 70 enclosing vessel of insulating material, a stationary contact within said vessel, a movable contact in cooperative relation with said stationary contact, metallic guiding means for said movable contact, a retractile spring coupled to said movable contact and to said vessel, and a 75

- resilient conductor connected to said movable contact and to said vessel, said conductor providing the sole leading-in connection to said movable contact.
5. 7. An electrical switching device comprising an enclosing vessel having a stem of insulating material, a stationary contact mounted within said vessel, a movable contact in cooperative relation with said stationary contact, guiding means for said movable contact including a plurality of metallic rods embedded in said stem, a metallic member held in said stem and terminating therein, a retractile spring coupled to said movable contact and to said metallic member, and an electrical connection between said movable contact and said stem including a folded metallic ribbon.
10. 8. An electrical switching device comprising an enclosing vessel, a stationary contact within said vessel, a movable assembly including a body portion having an aperture therein, guide members engaging said body portion, a plurality of resilient members each fixed at one end and connected to said assembly, only one of said members serving as a lead-in conductor for said assembly, a contact member within said aperture and disposed in cooperative relation to said stationary contact, and cushioning means within said aperture engaging said body portion and said second contact.
15. 9. An electrical switching device comprising an enclosing vessel having a stem, a stationary contact within said vessel, a plurality of rods extending from said stem, a magnetic member slidably mounted on said rods, a stop member on said rods adjacent one end of said magnetic member, a retractile spring connected to said stem and to said magnetic member, an electromagnet exterior of said vessel adapted to propel said magnetic member along said rods, and a contact resiliently mounted on said member and disposed in cooperative relation with said stationary contact.
20. 10. An electrical switching device comprising an enclosing vessel having a stem, a stationary contact within said vessel, a plurality of guide members extending from said stem, a magnetic member having an aperture therein and a plurality of grooves into which said guide members extend, a rod extending through said aperture having a collar at one end abutting against said magnetic member, a contact mounted on said rod and disposed adjacent said stationary contact, a helical spring within said aperture engaging said second contact and said magnetic member, an electromagnet adapted to move said magnetic member along said guide members, and a retractile spring coupled to said rod and to said stem.
25. 11. An electrical switching device comprising an enclosing vessel having a stem at each end thereof, a stationary contact mounted on one stem, a plurality of parallel rods extending from the other stem, a terminal on said vessel, a magnetic member of relatively large mass disposed in alignment with said stationary contact and having grooves the walls of which are engaged by said rods, a contact resiliently mounted on said magnetic member and disposed adjacent said stationary contact, an electromagnet surrounding said magnetic member, a retractile spring coupled to said magnetic member and to said stem, and a resilient conductor electrically connected to said second contact and to said terminal, said conductor forming the sole leading-in connection to said second contact.
